UNITED STATES PATENT OFFICE.

WILLIAM F. DRAPER, OF HOPEDALE, MASSACHUSETTS.

LOOM-SHUTTLE.

No. 807,478.

Specification of Letters Patent.

Patented Dec. 22, 1908.

Application filed May 7, 1908. Serial No. 431,349.

To all whom it may concern:

Be it known that I, WILLIAM F. DRAPER, a citizen of the United States, and resident of Hopedale, county of Worcester, State of Massachusetts, have invented certain new and useful Improvements in Loom-Shuttles, of which the following is a full, clear, and exact specification.

This invention pertains more especially to 10 loom shuttles adapted for the automatic insertion of a bobbin while the loom is in motion, and the invention has for its object the production of improved means for holding the bobbin in proper position in the shuttle, 15 such means being soconstructed and arranged that the incoming bobbin is brought into the control thereof more easily and with less expenditure of power than is generally necessary in shuttles of this type. The out-going bobbin can also be ejected with less force, so that not only is the necessary power of the transferring mechanism reduced but there is less wear and tear upon the bobbin-holding means and the bobbin itself.

20 One practical embodiment of the invention is herein illustrated, and fully described in the specification, the several novel features of the invention being particularly pointed out in the claims.

25 Figure 1 is a top plan view of one end of a shuttle, partly broken out, with one practical embodiment of my invention applied thereto; Fig. 2 is a partial vertical section, taken on the line 2—2, Fig. 3; Fig. 3 is a horizontal section on the line 3—3, Fig. 2. Fig. 4 is a transverse section on the line 4—4, Fig. 3, looking toward the left; Fig. 5 is a perspective view of one of the jaw-carriers; Fig. 6 is an inner face view of one of the 30 holding jaws.

Part of a shuttle-body is shown at 1, having a bobbin-receiving opening 2, extending through the shuttle from top to bottom, as usual in loom-shuttles adapted for the automatic insertion of a bobbin, and at one end the bobbin-opening is provided with my improved means for engaging and holding the bobbin in position.

Herein the jaws are made separate, each 40 consisting of an elongated metallic plate 3 having on one face a series of grooves 4 adapted to receive the usual annular projections or rings with which the head of a bobbin is provided. The jaws are alike in construction, but they are reversed when placed in the shuttle, as will appear, each jaw having

5 at its inner end prolongations or lugs 5, 6 adjacent its upper and lower edges, and at its outer end the jaw is recessed at 7, having a lug 8 adjacent one edge. Said jaws are 60 pivotally mounted within the bobbin opening, and herein I have shown the jaws independently pivoted and on fulcras substantially parallel to each other and to the longitudinal axis of the shuttle.

To sustain the jaws I provide each with a carrier, shown separately in Fig. 5, and made of metal, each carrier comprising a base portion 9 apertured at 10 and bent laterally at one end, as at 11, and then bent again to 70 form an extension 12, shown as parallel to the base and having an elongated opening 13 near one edge. The other edge of the extension is provided with an open eye 14 located at right angles to the extension, with a second eye 15 at the inner end of said extension, the bend 11 having a recess 16, best shown in Fig. 5. Both carriers are made alike, but are reversed when assembled in the shuttle, as will appear, so that the eyes 14, 15 of one 80 carrier will be turned toward the wall of the bobbin opening, near the top of the shuttle, while the out-turned eyes of the other carrier will be located near the bottom of the shuttle and facing the adjacent wall.

85 The shuttle-body is recessed longitudinally from the end of the opening 2, as at 17, the end wall 18 being rounded as shown in Figs. 1 and 2, and into this recess the bases 9 of the carrier are inserted, a metallic separator 19 being placed between them and having a suitable opening 20, Fig. 2, to receive the retaining bolt 21 extended transversely through the shuttle-body and the base apertures 10. The rear end of the separator is 90 shaped to fit the curved end 18 of the recess 17, and it is wider than the body of the separator, leaving upright shoulders 22 against which the inner ends of the carrier-bases abut, said separator having a laterally enlarged head 23 which overhangs the upper edges of the bases, the lower edges of the latter and of the separator resting on the bottom 24 of the recess.

95 By the construction described the bases of the jaw-carriers are rigidly held in place in the shuttle, with the extensions 12 resting against the recesses 25 formed in the opposite walls of the bobbin opening 2. It will be apparent, however, that the eyes 14 and 15 of one carrier will be near the top of the shuttle and the similar eyes on the other carrier

will be near the bottom of the shuttle, due to reversal of said jaw-carriers.

The lugs 5 and 8 of each jaw constitute pintles and are loosely inserted in the eyes 15 and 14 respectively, in assembling, and before the eyes are closed by the adjacent shuttle-wood, so that each jaw is pivotally connected with its carrier and can swing toward or from the center of the shuttle, such movement being limited by the lug 6 of a jaw entering the recess 16 in the bend 11 of its carrier.

Viewing Fig. 4 it will be seen that the right hand jaw 3 is fulcrumed at its upper edge and 15 the oppositely located, left-hand jaw is fulcrumed at its lower edge, the jaws being yieldingly held in substantial parallelism but inclined with relation to the walls of the shuttle.

20 I have herein shown the yielding control effected by springs 26 held in the openings 13 and bearing against the free, adjacent portions of the jaws, the springs being of any suitable character, such as blocks of rubber, 25 though I do not restrict myself thereto.

Referring to Fig. 4 it will be seen that the upper edge of the left-hand jaw may swing outward to widen the opening between the jaws to admit the head of an incoming bobbin, the operative position of the head being 30 indicated by the dotted circle 27, and the lower edge of the right-hand jaw can move outward, or to the right, Fig. 4, when a bobbin is ejected. This arrangement provides 35 for a very easy insertion of a bobbin into holding position between the jaws, reducing the power required to effect such insertion, and also makes the ejection of a bobbin easier, while reducing the strain upon the 40 various parts of the holding means and the shuttle itself.

As the jaws are precisely alike they are interchangeable, as are the carriers, and both parts can be easily and cheaply constructed 45 from strap metal of proper character.

I do not restrict my invention to the construction and arrangement described in detail herein, as the same is but one practical embodiment of my invention and may be 50 varied in different particulars without departing from the scope of my invention as set forth in the claims annexed hereto.

Having fully described my invention, what I claim as new and desire to secure by Letters Patent is:—

1. A loom-shuttle adapted for the automatic insertion of a bobbin, having separate jaws mounted thereon to engage and hold a bobbin between them, independent pivots 60 for the jaws, and means coöperating with the jaws to maintain them yieldingly in operative position.

2. A loom-shuttle adapted for the automatic insertion of a bobbin, having opposed, 65 independently movable pivoted jaws thereon

to yieldingly engage and hold a bobbin between them, said jaws forming the sole support for the bobbin, and parallel fulcra for and about which the jaws are movable.

3. In a loom-shuttle having an opening 70 for the reception of a bobbin, opposed, yieldingly controlled pivoted jaws to engage and hold between them the head of a bobbin and constitute the sole support therefor, and fulcra for said jaws substantially parallel to the longitudinal axis of the shuttle.

4. A loom-shuttle adapted for the automatic insertion of a bobbin, having opposed, independently movable jaws to yieldingly 80 engage and hold a bobbin, one of said jaws being pivotally sustained near the top, and separate means to pivotally sustain the other jaw near the bottom of the shuttle.

5. Bobbin-holding means for loom-shut- 85 tles, comprising relatively fixed carriers, oppositely located bobbin-engaging jaws pivotally mounted on the carriers, and yielding means for and to normally maintain each jaw in operative position.

6. Bobbin-holding means for loom-shut- 90 tles, comprising oppositely located bobbin-engaging jaws, means to pivotally support said jaws, one adjacent its upper longitudinal edge and the other adjacent its lower 95 edge, and means acting at the free edges of the jaws to maintain them yieldingly in operative position.

7. In a loom-shuttle having a bobbin-receiving opening, opposite holding-jaws having their inner faces normally in parallelism and inclined with relation to the walls of the bobbin-receiving opening, and means to maintain the jaws in yielding engagement with a bobbin.

8. In a loom-shuttle having a bobbin-receiving opening, opposite pivoted holding-jaws having their inner faces normally in parallelism and inclined with relation to the walls of the bobbin-receiving opening, fulcra 110 for the jaws substantially parallel to the longitudinal axis of the shuttle, and means to maintain the jaws yieldingly in operative position, the jaws constituting the sole support for the bobbin.

9. In a loom-shuttle adapted for the automatic insertion of a bobbin, two opposed and movable jaws to engage and hold between them the head of a bobbin, separate and independent pivots for the jaws, and 115 yielding means acting upon and to normally maintain the jaws in operative position.

10. In a loom-shuttle adapted for the automatic insertion of a bobbin, yieldingly controlled, horizontally pivoted bobbin-holding jaws laterally separable at their upper edges by entrance of a bobbin therebetween.

11. In a loom-shuttle having a bobbin-receiving opening, relatively fixed and sub- 130

stantially parallel carriers extended longitudinally into the opening, holding jaws pivotally mounted on the carriers, and yielding means interposed between the jaws 5 and carriers to maintain the jaws in operative position.

12. In a loom-shuttle adapted for the automatic insertion of a bobbin, opposed, independent holding jaws to coöperate with the bobbin, a separate pivotal support for each jaw adjacent one edge thereof, and substantially parallel to the longitudinal axis of the shuttle, and means acting on the free edges of the jaws to maintain them 15 yieldingly pressed inward.

13. In a loom-shuttle adapted for the automatic insertion of a bobbin, two oppositely located and movable holding jaws, a separate and independent pivot for each 20 jaw, means to act upon the jaws and maintain them yieldingly in engagement with the head of a bobbin inserted therebetween, and means to limit movement of the jaws.

14. Bobbin holding means for loom-shuttles, comprising two like and reversely positioned jaw-carriers, jaws pivotally mounted on the carriers and having their inner faces shaped to engage and hold the head 25

of a bobbin, and means interposed between each carrier and the jaw mounted thereon 30 to yieldingly maintain the jaw in operative position.

15. Bobbin holding means for loom-shuttles, comprising two opposed like jaws reversely pivoted, carriers rigidly mounted on 35 the shuttle, and on which the jaws are pivoted, and yielding means to control the movements of the jaws.

16. Bobbin holding means for loom-shuttles, comprising two like and reversely positioned jaw-carriers, each having a flat base and a laterally offset extension provided with eyes, a separator interposed between the bases, means to hold said bases and separators rigidly to the shuttle-body, a jaw 45 having pintles pivotally mounted in the eyes of each carrier, and means to yieldingly control pivotal movement of the jaws.

In testimony whereof I have signed my name to this specification in the presence of 50 two subscribing witnesses.

WILLIAM F. DRAPER.
